Erwin B. Eiring

UNITED STATES PATENT OFFICE.

WALTER J. BLIFFERT, OF MILWAUKEE, WISCONSIN.

MANIFOLD GASKET.

Application filed April 16, 1923. Serial No. 632,447.

To all whom it may concern:

Be it known that WALTER J. BLIFFERT, a citizen of the United States, and resident of Milwaukee, in the county of Milwaukee, 5 and State of Wisconsin, have invented certain new and useful Improvements in Manifold Gaskets; and I do hereby declare that the following is a full, clear, and exact description thereof.

10 This invention relates to attachments for the intake manifolds of internal combustion engines for diluting the gas stream, and is particularly directed to a manifold gasket.

15 Objects of this invention are to provide a device adapted to be positioned within the intake manifold of a gasoline engine providing means for the introduction of air into the gas stream, which will insure adequate and thorough mixing of this incoming 20 air with the flowing gas stream, which will improve the atomization of the fuel, and which will not restrict the free flowing of the gas stream.

25 Further objects are to provide a gasket which may be inserted between the carburetor and the intake manifold of the standard types of gas engines without requiring any further alteration, and which will insure mixing of the fresh air and the gas 30 stream, which will introduce such air at the portion of the gas stream which is most heavily loaded with fuel and which will atomize any liquid fuel that may collect upon the bottom of the intake pipe.

35 An embodiment of the invention is shown in the accompanying drawings, in which:

40 Figure 1 is a fragmentary view of a carburetor and intake manifold showing the gasket in position, a portion of the view being in section to more clearly illustrate the construction.

45 Figure 2 is an enlarged view of the gasket removed from other portions of the apparatus.

50 Figure 3 is a section on the line 3—3 of Figure 2, showing the gasket in the position that it occupies when in use, and illustrating particularly the lower portion of the gasket.

55 Between the flanges 1 of the carburetor 2 and the flanges 3 of the intake manifold 4 the gasket 5 is positioned. This inserting of the gasket may be readily accomplished in standard equipments by merely loosening the connecting bolts (not shown) and slipping the gasket in position. This operation

is greatly facilitated by providing a substantially horizontal open notch 6 on one side of the gasket for the reception of one of the bolts and providing an upwardly opened notch 7 upon the other side of the gasket for the reception of the other attaching bolts, whereby the gasket may be slipped into position with the notch 6 surrounding one of the bolts and may thereafter be pivoted about such bolt and rocked into its correct position—the notch 7 passing over the other bolt during this process. When in position the central aperture 8 of the gasket aligns within the interior of the pipes. A 70 lip 9 formed integrally with the gasket extends upwardly and to the rear in a manner as illustrated particularly in Figures 2 and 3. This lip 9 is provided with a channel 10 which gradually deepens as the body portion of the gasket is approached and finally passes completely through the gasket, thereby forming the slot 11 through the body of the gasket.

75 The point at which the channel 10 merges into the slot 11 is approximately the point where the gasket is gripped between the flanges 1 and 3, as may be seen from Figure 3.

80 The operation of the apparatus is as follows:—The suction draws air inwardly through the slot 11 and the channel 10 and the incoming air is directed rearwardly, as is indicated by the arrows in Figure 1. This inwardly directed air contacts with the outwardly flowing stream of gas and violently commingles therewith. It is to be noted that this mixing occurs adjacent the lower portion of the stream and extends in a less pronounced manner towards the upper portion. 95 The lower portion of the gas stream usually contains the greatest amount of fuel and is consequently densest and thus the dilution is needed more at this portion of the stream than at any other portion.

100 It is also to be noted that the liquid, which collects or condenses upon the walls of the pipe, gradually passes to the lower portion and is stopped by the lip 9. This thin liquid film is rapidly vaporized by the upwardly and inwardly directed stream of air, so that no solid particles of fuel are carried into the engine cylinders.

105 It will thus be seen that means have been provided for mixing with the inwardly passing fuel fresh air in a manner to insure adequate atomization and complete mixing.

It will further be seen that a manifold gasket has been provided which will accomplish the above enumerated functions, which may be readily inserted in position, and which may 5 be cheaply and readily manufactured.

Although one specific form of the invention has been described in considerable detail, it is to be understood that the invention may be variously embodied and is to be 10 limited only as defined by the appended claims.

I claim:-

1. A manifold gasket adapted to be positioned between adjacent flanges of the intake system of an internal combustion engine, said gasket comprising a body portion having an aperture corresponding to the bore of the intake system and having an integral lip extending into said bore, said lip 15 curving from the plane of the gasket and having a channel formed therein, said body portion having a slit therethrough extending outwardly from said channel.

2. A manifold gasket adapted to be positioned between adjacent flanges of the intake system of an internal combustion engine, said gasket comprising a body portion

having outwardly extending slotted wings with the slots therein extending at substantially right angles to each other, said body portion having an aperture corresponding to the bore of the intake system, and having an integral lip extending upwardly from the lower portion of said gasket and curved out of the plane thereof as the inner end of 35 the lip is approached, said lip having a groove therein, and said gasket having a slot communicating with said groove.

3. A manifold gasket adapted to be positioned between adjacent flanges of the intake system of an internal combustion engine, said gasket having an aperture corresponding to the bore of the intake system and having a curved lip projecting upwardly 40 into said aperture, said lip being concaved on one side, and said gasket having a hole 45 passing therethrough from the outside to the aperture and opening on the concaved side of said lip.

In testimony that I claim the foregoing I 50 have hereunto set my hand at Milwaukee, in the county of Milwaukee and State of Wisconsin.

WALTER J. BLIFFERT.
